UNITED STATES PATENT OFFICE.

PLINY PATRICK, OF CINCINNATI, OHIO.

DESIGN FOR A BASE FOR DISPLAY CHARACTERS.

SPECIFICATION forming part of Design No. 33,483, dated October 30, 1900.

Application filed May 10, 1900. Serial No. 16,234. Term of patent 7 years.

To all whom it may concern:

Be it known that I, PLINY PATRICK, a citizen of the United States, residing at Cincinnati, in the county of Hamilton and State of Ohio, have invented and produced a certain new and useful Design for Bases for Display Characters, of which the following is a specification.

In the drawings, Figure 1 represents a front elevation of a base for one of the display characters, and Fig. 2 a horizontal section of Fig. 1.

The base consists of a substance having a blank surface A, provided with inclined bars B, of varying length. 15

I claim—

The design for a base for display characters, substantially as herein shown and described.

PLINY PATRICK.
